UNITED STATES PATENT OFFICE

HAROLD E. DONLEY, AUGUSTUS J. FRAME, AND JACKSEN G. GILMORE, OF COLUMBUS, OHIO, ASSIGNORS TO FRANKLIN OIL HEATING, INCORPORATED, OF COLUMBUS, OHIO, A CORPORATION OF OHIO

OIL BURNING APPARATUS

Application filed September 4, 1928. Serial No. 303,673.

This invention relates to improvements in oil burning apparatus and has particular reference to apparatus of the character adapted for the heating of residential properties, buildings and the like, one of the outstanding objects of the invention being to provide apparatus of this character which is simple in construction and reliable and efficient in operation.

10 It is another object of the invention to provide an oil burner system consisting of but few and simple mechanical parts and wherein silent operation is secured.

15 It is another object of the invention to provide an oil burner system which may operate to secure pilot combustion by means of the liquid oil used as the fuel for the system. It has been customary heretofore to employ in connection with such oil burning systems, 20 oil as the primary source of fuel and gas as a secondary source of fuel for the purpose of supporting combustion of a pilot flame, which remains in a constant state of combustion to provide for the intermittent flow of 25 the main fuel body to the combustion apparatus. In the present invention provision is made whereby the single fuel may be employed to satisfy the requirements of both principal and pilot combustion.

30 It is a further object of the invention to regulate the flow of air to the combustion apparatus in such a manner that clogging of the apparatus with carbon or soot deposits will be prevented for the purpose of securing 35 sustained, efficient and continuous operation.

With these and other objects in view which will appear as the description proceeds, the invention consists in the novel features of construction, combinations of elements and 40 arrangements of parts hereinafter to be fully described and pointed out in the appended claims.

In the accompanying drawing:

45 Figure 1 is a fragmentary view in side elevation and partly in vertical section of oil burning apparatus constructed in accordance with the present invention,

Figure 2 is a top plan view of the apparatus set forth in Figure 1,

50 Figure 3 is a vertical sectional view on a

larger scale disclosing more particularly the construction of the combustion pot and the oil and air lines leading thereto,

Figure 4 is a horizontal sectional view on line 4—4 of Fig. 3 of the structure set forth in 55 Figure 3, and

Figure 5 is a horizontal sectional view on the line 5—5 of Figure 3.

Referring more particularly to the drawing, the numeral 1 designates the improved 60 oil burning apparatus comprising the present invention in its entirety. The apparatus comprises broadly a combustion vessel or pot 2, the latter being arranged within the combustion chamber 3 of a furnace or other suitable type of heating unit 4. Leading to the pot 2 is an air conduit 5 which has its outer end disposed in communication with a motor driven fan or blower 6. Also entering the bottom of the vessel or pot 2 is a liquid oil line or conduit 7, which extends substantially parallel with and within the air line 5, as shown more particularly in Figures 3 and 4. This oil line communicates with a main control valve 8, which in this instance is of the 65 magnetically operated type and is disposed within a circuit 9 which includes a source of energy 10 and a thermostatic switch 11. When the circuit 9 is completed by the switch 11 the valve 8 is elevated or opened to permit 70 of the flow of oil through the oil line 7 to the burner pot 2. Also, the oil line is provided with a float 12 by means of which a pre-determined liquid level is maintained within the vessel or pot 2 when the apparatus is in active 75 operation, the float controlling automatically the flow of oil from a source of supply, such as a tank (not shown).

The vessel or pot is provided with an open top and around the outer and upper portion thereof the said vessel includes an annular flange 13 which is received within a sheet metal casing 14 formed to effect the elevated support of said vessel above the base or floor line. The flange 13 is apertured as at 15 so as 80 to permit of the passage of air therethrough, the casing 14 being in open communication with the inner or discharge end of the conduit 5 so that air may flow freely under relatively low pressure from said conduit and 85 90 95 100

through the apertures 15 to commingle with the oil vapors released from the oil body which is normally maintained within the vessel 2.

6 In this instance the vessel 2 includes a vertical and axially upstanding sleeve 16, in the upper end of which is situated an air distributor 17. This distributor comprises a tubular body provided with a pair of heads 18 and 19. The lower head 19 is formed with apertures 20 which direct streams of air into the vessel 2 for the purpose of effecting a combustible mixture of efficient proportions but to prevent the occurrence of active combustion 15 of the oil within the confines of the vessel or pot. The air released from the apertures provided in the upper head 18 combines with the fuel mixture in a plane above the vessel or pot 2 and likewise so does the air discharged 20 from the apertures 15 of the flange 13. This arrangement provides for the economical and efficient consumption of liquid oil and produces a system which operates effectively under relatively low air pressures and without 25 atomization of the oil.

In this instance the bottom of the vessel or pot 2 is provided with a depending integral enlargement 21 provided with a bore 22 into which is positioned the forward end of the 30 oil line 7, the opposite end of said bore entering, as shown in Figure 3, the bottom of the vessel or pot 2. The enlargement 21 is also provided with a second bore 23 which communicates with the bore 22 by means of 35 the downwardly and angularly extending port 24, and which communicates with an upwardly and angularly extending port 25, the converging ends of the ports 24 at 25 being closed by means of a removable plug 26, 40 the latter permitting of the drilling of the angularly arranged ports. One end of the bore 23 is closed or blind, while the opposite end receives an air conveying pipe 27 which extends substantially parallel with the oil 45 line 7 for a distance and then extends upwardly and at an angle to said oil pipe. The upper end of the pipe 27, which is situated in the air conduit 5, terminates in a substantially inverted U shaped fitting 28, which 50 terminates finally in the interior of the air conduit 5, so that the air may be withdrawn from the conduit 5 and forced under pressure through the pipe 27 and into the oil flowing through the line 7 by way of the 55 ports 24 and 25. The air which passes through the line 27 thus mixes with the oil for the purpose of producing during the inactive operation of the apparatus an oil pilot flame.

60 As previously stated, the operation of the apparatus is intermittent, that is, when the temperature of the zone being heated reaches a certain point the thermostatic switch 11 functions to automatically close the magnetic valve 8. This valve when in its closed posi-

tion permits of the flow of a relatively small quantity of oil through the line 7, and this reduced quantity of oil then combines with the air, obtained from the pipe 27, thus producing a combustible mixture suitable for 70 use as a pilot flame enabling the oil to be used for the pilot flame rather than gas obtained from another source or origin. It will be understood that the motor which operates the fan or blower 6 continues to function at 75 full operation regardless of the amount of oil flowing through the oil line. This enables the air flowing through the line 27 to be maintained constant at all times, which permits the air not only to serve for the purpose of producing a pilot flame mixture but also to remove by reason of its velocity and mechanical contact any carbon particles which may tend to accumulate in the oil line 80 and obstruct oil flow. In the present instance the formation of carbon is practically prevented due to the fact that active combustion is maintained at all times. In other words when the system is operating at full capacity the mixture of oil and air is so efficient as to prevent the formation of soot or carbon deposit, and this is likewise true when the pilot flame is employed, since the relative amounts of air and oil are such as to secure smokeless combustion. If for any reason 85 free carbon should be present the same is ejected from the system by the force of the air flow through the line 27.

We preferably provide a slidable control shutter 29 in the conduit 5 at a point between the air entrance into the fitting 28 and the pot 2. It has been found that this installation requires that various amounts of air shall be delivered by the conduit 5 to the main air outlets of said vessel. Thus a small building requires less air, under uniform conditions, than a large house or building. However, to secure the best operation of the oil pilot apparatus uniform air pressure should flow through the line 17 irrespective 100 of the size of the building being heated. It will thus be seen that regardless of the amount of opening in the duct 5 as regulated by shutter 29 the auxiliary air duct 27 will receive its full supply of air from the fan 6. 105

In view of the foregoing it will be seen that the present invention provides simple yet effective oil burning apparatus which may operate economically and at relatively low air pressure. The system avoids specifically the atomizing of oil by means of high pressure apparatus, such as pumps and nozzles. This permits the system to operate not only efficiently but silently, which is a decided advantage in house heating equipment. Further, the apparatus necessary to carry out the operation is greatly simplified and reduced in cost. This system provides for continuous operation and full efficiency, permits the employment of an oil pilot flame, rather 110 115 120 125 130

than the use of a gas pilot flame, and further-
more provides sustained operation by pre-
venting the formation of obstructing carbon
deposits in the essential oil passages of the
system.

5 What is claimed is:

1. In oil burning apparatus, an open topped
burner vessel, an oil line leading thereto, a
valve in said line operable when open to per-
mit full oil flow through the line and when in
closed position to permit a slight oil flow
therethrough for a pilot light, an air supply
conduit for said vessel, means for constantly
maintaining air under pressure in said con-
duit, and a supplemental air supply line com-
municating at one end with the interior of
said conduit and at its other end with the in-
terior of said oil line and connected at a
point immediately below the oil level which
20 is maintained for pilot light operation.

2. In oil burning apparatus, an open
topped burner vessel, an air supply conduit
for said vessel, means for constantly main-
taining air under pressure in said conduit,
25 an oil line entering said vessel, a valve in said
line operable when in open position to main-
tain a quantity of oil distributed over a large
area in said vessel for maximum combustion
operation, said valve when in a closed posi-
30 tion permitting of a slight oil feed through
the oil line to restrict the quantity of oil to
a small area in said vessel for pilot light op-
eration, and a supplemental pipe line for de-
livering air from said conduit to the oil for
35 said pilot light.

3. In oil burning apparatus, an open
topped burner vessel, an oil line leading to
said vessel, a valve in said line operable in one
position to permit maximum flow of oil
40 through said line to maintain the oil within
the vessel over the full area thereof and in
another position to restrict the flow of oil
through the line to the area comprising the
inlet opening for the oil to effect pilot light
45 combustion within said vessel, a main air
conduit leading to said vessel, means for
maintaining air under pressure in said con-
duit for combustion of the main oil supply,
and a supplemental air line connected at one
50 end to the main air conduit and its other end
at the oil line at a point adjacent the pilot
light combustion zone.

4. In oil burning apparatus, a burner ves-
sel having an oil inlet in the bottom thereof,
55 an oil line connected to said inlet, a valve in
said oil line and movable from a position
wherein full oil supply to said vessel is per-
mitted for the maintenance of a large fuel
area therein to a position wherein a restricted
60 oil supply is delivered to said vessel for main-
taining the oil to the area comprising the oil
inlet for pilot light operation, a main air con-
duit for said vessel, means for maintaining
air under pressure in said conduit for the com-
65 bustion of the main oil supply within said

vessel, and a supplemental air line leading
from said conduit to the oil inlet of said ves-
sel at a point immediately below said inlet
opening.

5. In oil burning apparatus, an open
topped burner vessel having an enlargement
formed with said bottom thereof and ar-
ranged below the latter, said enlargement
being provided with a bore having direct
communication with the interior of said ves-
sel and forming an oil pocket therein, a sup-
ply line connecting said bore for conducting
liquid fuel into the bottom of said vessel, an
air supply conduit for said vessel, means for
maintaining air under pressure in said con-
duit, a valve in the oil line operable to main-
tain the oil over a large area in the vessel
during the main operation of said burner and
to restrict the oil area to the size of said inlet
or pocket for pilot light operation, and means
for supplying air from said air conduit to
the oil line at a point adjacent said oil pocket.

In testimony whereof we affix our signa-
tures.
